[57] CLAIM

The ornamental design for automobile steering lock, as shown and described.

DESCRIPTION

FIG. 1 is a top, front, and right side perspective view of automobile steering lock showing my new design;
FIG. 2 is a front elevational view thereof;
FIG. 3 is a rear elevational view thereof;
FIG. 4 is a left elevational view thereof;
FIG. 5 is a right elevational view thereof;
FIG. 6 is a top plan view thereof;
FIG. 7 is a bottom plan view thereof; and,
FIG. 8 is a reduced top, front, and right side perspective view thereof, with the broken-line disclosure of a portion of a steering wheel and dashboard being shown for illustrative purposes only and forming no part of the claimed design.

FIG. 1

FIG. 2

FIG. 3

FIG. 5

FIG. 4

FIG. 6

FIG. 7

FIG. 8
